UNITED STATES PATENT OFFICE.

CLIO B. YAW, OF ARLINGTON, NEW JERSEY, ASSIGNOR TO REMINGTON TYPEWRITER COMPANY, OF ILION, NEW YORK, A CORPORATION OF NEW YORK.

TYPE-WRITING MACHINE.

1,114,218.

Specification of Letters Patent. Patented Oct. 20, 1914.

Application filed April 18, 1913. Serial No. 762,114.

To all whom it may concern:

Be it known that I, CLIO B. YAW, a citizen of the United States, and resident of Arlington, in the county of Hudson and State of New Jersey, have invented certain new and useful Improvements in Type-Writing Machines, of which the following is a specification.

My invention relates to paper feeding and controlling mechanism for typewriting machines and its general object is to provide an improved mechanism of the character specified and which is adapted for a variety of uses.

Specifically the present invention has for its object the improvement in various respects of the tally strip mechanism disclosed in my prior application, Serial No. 746,303, filed February 5, 1913.

Various other objects will appear in the course of the following specification.

To the above ends my invention consists in the features of construction, combinations of devices and arrangements of parts hereinafter described and particularly pointed out in the claims.

In the accompanying drawings, Figure 1 is a fragmentary end elevation of the upper part of a No. 11 Remington typewriting machine embodying my invention, some of the parts being shown in section. Fig. 2 is a vertical sectional view taken on a plane indicated by the dotted line $z-z$ in Fig. 1 and looking in the direction of the arrows at said line. Fig. 3 is a central vertical longitudinal sectional view of the platen. Fig. 4 is a transverse sectional view taken on a plane indicated by the dotted line y in Fig. 3 and looking in the direction of the arrow at said line, certain of the paper feeding devices, not shown in Fig. 3, being shown in full lines in Fig. 4. Fig. 5 is a top plan view of the paper feeding devices shown in Fig. 4. Fig. 6 is a transverse sectional view taken on a plane indicated by the dotted line x in Fig. 3 and looking in the direction of the arrow at said line. Fig. 7 is a view corresponding to Fig. 6 but with the paper feeding devices locked out of operation and shown in section. Fig. 8 is a top plan view of the paper feeding devices shown in Fig. 6. Fig. 9 is a vertical sectional view taken

on a plane indicated by the dotted line v in Fig. 6 and looking in the direction of the arrow at said line. Fig. 10 is an enlarged fragmentary top plan view of parts of the line spacing mechanism illustrated in Figs. 1 and 2 but showing the parts set in different relations from the first named figures. Fig. 10^a is an enlarged horizontal sectional view taken on planes indicated by the broken dotted line u in Fig. 1 and looking downward as indicated by the arrow at said line. Fig. 11 is an end view partly in section of the pawl shifting mechanism, the section being taken on a plane indicated by the dotted line t in Fig. 10 and looking in the direction of the arrow at said line. Fig. 12 is an inclined sectional view taken on a plane indicated by the dotted line s in Fig. 1 and looking in the direction of the arrow at said line. Fig. 13 is a central vertical longitudinal sectional view taken through the tally delivery holder or carrier. Fig. 14 is a substantially horizontal sectional view taken on a plane indicated by the dotted line g in Fig. 1 and looking in the direction of the arrow at said line. Fig. 15 is a fragmentary longitudinal sectional view on a reduced scale taken centrally of the platen and showing a modification of the platen construction.

As appears from Figs. 1 and 2 the main frame of the machine comprises posts 1 supporting a top plate 2 from which rise lugs 3 on which are supported grooved guide rails 4 that coöperate through anti-friction balls 5 with a front bar 6 and rear bar 7 of a carriage truck which further includes end bars 8 connecting the front and rear bars. Devices 9 shiftably connect with said truck a platen frame or carrier comprising end bars or plates 10 and further including cross rods or bars 11 and 12. The platen frame and the supporting truck constitute a traveling platen carriage. The end bars 10 provide bearings for stub shafts 13 and 14 to the outer ends whereof are secured finger wheels 15. The shafts 13 and 14 assist to support a two-part or divided platen best illustrated in Fig. 3. The main or longer section or element of the platen 16 is arranged coaxially with and at the left of the supplementary or tally section 17 of the platen.

These elements, sections or parts 16 and 17 may be considered as platens in themselves. The main platen 16 comprises a core 18 of wood and a sheath 19 of rubber and has secured to its left end by wood screws 20 which screw into the core a platen 21 having an outwardly extending hub 22 which is secured in set relationship with the shaft 13 by a set screw 23. Arranged within the core 18 and frictionally engaging therewith is a tube or supporting device 24 provided at its left end with inturned ears 25 through which the tube 24 is secured by screws 26 to the platen head 21 and consequently to the platen 16. The sleeve 24 extends rightwardly beyond the platen 16 and is provided at its right-hand end with inturned ears 27 which receive screws 28 by which the sleeve 24 and platen 16 are connected with clutch devices for releasably connecting the platen 16 with its ratchet wheel 29. Said clutch devices are of the construction found in the Remington No. 11 typewriting machine and substantially disclosed in the patent to Woodward, No. 945,358, dated January 4th, 1910 and include a clutch carrier comprising a main hub 30 provided with slots 31 which receive clutch members 32 that engage with and clutch an inward rib 33 on the ratchet wheel 29 and are releasable to disengage said rib by rollers 34 which coöperate with the inner free ends of said clutch members 32. Said rollers are mounted in a frame 35 which is secured to the inner end of the shaft 14, which is adapted to slide through the hub 30 and is pressed outward normally by a spring (not shown) contained in a barrel 36 secured to the hub 30. The rib 33 bears rotatably on the hub 30 and is undercut to bear on a plate 37 which is secured to the hub by the screws 28 that pass through the hub and are threaded into the ears 27. It will be understood that normally the clutch members 32 hold the ratchet wheel 29 in fixed relationship with the sleeve 24 and the platen 16 so that line spacing movements communicated to the wheel 29 by devices hereinafter described will be transmitted to the platen 16. When, however, the right-hand finger wheel 15 is pushed in it causes the rollers 34, acting on the clutch members 32, to disconnect the ratchet wheel from the platen 16 so that the platen may be turned independently of its ratchet wheel. The ratchet wheel is held from displacement on the hub 30 by the plate 37 at one side and by a double flange 30^a on the hub at the opposite side. If desired, the clutch members may be locked in released position by devices comprising a flange 39 rigid with the shaft 14 and coöperative with a detent 40 pivoted at 41 in a slot in a collar 42 that is secured by a screw 43 to a sleeve 44. Coöperative with said detent is a spring 45. The sleeve 44 is bored out to provide a passage for the

shaft 14 and is counterbored at its left end to receive the reduced or secondary hub portion 46 projecting rightward from the main hub 30. Said sleeve 44 is threaded into the right-hand end plate 10 of the platen frame 70 and is secured in fixed relationship thereto by a check nut 47. At its left, inside the end bar 10, said sleeve terminates in a flange 48. The tally platen 17 is rotably mounted on the tube 24 to the right of the platen 16 and comprises a tube or core 49 surrounded by a sheath 50 of rubber. The tube 49 is secured at its left end on a shouldered platen head or annulus 51 which abuts against the platen 16 and bears rotatably on the tube 24. At its 75 right end the tube 49 is secured to a platen head 52 which is shouldered and notched to provide a seat for the tube 49 and is provided at its periphery with gear teeth 53, thus becoming in effect a gear wheel. The 80 platen 17 comprising the heads 51 and 52, core or tube 49 and sheath 50 is in effect a single member and while it may turn on and relatively to the tube 24 is prevented from endwise displacement thereon, being confined between the platen 16 and an annular paper controlling device 54 which fits over and is suitably secured to the right end portion of the tube or sleeve 24 so that said device always turns with said sleeve and with 85 the platen 16. The periphery of the circular device 54 is knurled or roughened for the purpose of feeding paper in coöperation with the platen as hereinafter described. Arranged on the projecting end portion of the tube 24 to the right of the feeding device 54 is a gear wheel 55 which is adapted to turn freely on the tube 24 and has teeth corresponding with the gear 53 which is at the left of said device 54. To the right of the 90 gear wheel 55 and adjacent to the ratchet wheel 29 is a ratchet wheel 56 which bears rotatably on the double flange 30^a and is provided with ratchet teeth that coöperate with devices hereinafter described to provide for 95 line spacing movements which are transmitted from the ratchet wheel 56 to the gear wheel 55 by a pin or device 57 which projects laterally from the ratchet wheel and fits into a hole in the gear wheel 55. The motion of the gear wheel 55 is in turn transmitted to the gear wheel 53 by trains of devices hereinafter described. The ratchet wheel 56 is provided with a circular rib 56^a which abuts against the gear wheel 55 and prevents leftward displacement of the ratchet wheel 56. The teeth of said ratchet wheel correspond in number and in form with the teeth of the ratchet wheel 29 with which they may be brought into register, the two ratchet wheels being adapted to coöperate in alternation or simultaneously with line spacing devices hereinafter described.

Paper feeding devices preferably of the usual Remington construction coöperate

with the platen 16, said devices comprising as shown in Figs. 1 and 2, a main feed roller 58 and a secondary feed roller 59, the sections whereof protrude through slots in a 5 paper apron or deflector 60. Said deflector extends throughout the lengths of both platens and the forward upper edge of the portion opposite the tally platen is serrated as indicated at 61 to provide a paper cutting 10 edge. The feed rollers 58 and 59 may be mounted on supports or carriers of ordinary construction and are releasable by the usual releasing devices comprising a rock shaft 62 provided with releasing lugs or fingers 63, 15 said rock shaft extending throughout the lengths of both platens and being supported at its ends from the end bars of the platen frame. A releasing arm or finger piece 64 is secured to the rock shaft 62 near its left-hand end and when pushed rearward turns the shaft and causes the lugs 63 thereon, acting against the feed roll carriers, to release or throw the feed rollers 58 and 59 away from the platen 16.

20 25 The platen 16 and its feeding devices are adapted to feed a main sheet which is or may be arranged in superposed relationship with the tally sheet or strip that is fed over the tally platen. In some cases a short main sheet is employed which coöperates only with the right-hand sections of the feed rollers 58 and 59 and in practice it is found sometimes that these short sheets become skewed or displaced during feeding operations owing to 30 the fact that their right-hand portions are uncontrolled. Chiefly to remedy this and similar defects supplemental paper feeding devices are provided for coöperation with the right-hand marginal portion of the main 35 sheets that extend rightward over and beyond the tally platen 17. Said supplemental devices are arranged at the right of the tally platen and include the knurled annulus or circular device 54. Coöperative with said 40 device are short pressure or feed-rolls 65 and 66 which, as illustrated in Figs. 2, 4 and 5, are mounted in a rocking frame or carrier comprising parallel bars 67 spaced apart by a washer 68 and connected by a screw 69 45 which passes through said washer. The pressure rolls 65 and 66 are pivoted respectively at 70 and 71, the larger roll at the rear co-operating with the rear under side of the device 54 and the smaller roll 66 at the forward under side of said device. The rocking frame is pivotally supported on a rod or pin 72 extending laterally from the forward arm 73 of a three-armed lever which further comprises arms 74 and 75.

50 55 60 65 60 A nut 76-threaded on the outer end of the rod 72 prevents displacement of the rocking frame therefrom. The three-armed lever is pivoted on a rod or bar 77 near its right-hand end, being prevented from accidental displacement by a nut 77. This rod 70 is

preferably the same rod that provides a support for the feed rollers 58 and 59, said rod extending from end to end of the carriage and being supported on L-shaped hangers 78 which are secured to the bar 11 of the 70 platen frame. The release rock shaft 62 passes through openings in the upwardly extending arms of said hangers 78. Near its right-hand end the rock shaft 62 is provided with a downwardly extending finger 75 79 that is adapted to coöperate with the upper end of the lever arm 74 to turn the three-armed lever on its fulcrum, overcoming a draw spring 80 connected to the arm 75. The pressure rolls 65 and 66 are normally 80 maintained in spring pressed engagement with the knurled periphery of the device 54 by the spring 80 and will coöperate with said annulus to feed or advance the work sheet whenever the platen 16 is turned, the 85 annulus being rigidly connected to turn with said platen as will be set forth. When the release arm or key 64 is pushed rearward it will not only operate through the lug 63 to release the feeding devices of the 90 main platen 16 but will also operate concurrently through the finger 79 acting on the arm 74 to swing the three-armed lever upon its rod or axis 77, overcoming the 95 spring 80 and throwing off or releasing the pressure rolls 65 and 66.

95 100 105 110 115 120 125 130 Pressure or feeding devices are also provided for coöperation with the tally platen 17, said devices as illustrated in Figs. 2 and 6 to 9 comprising a pressure roll 81 coöperative with the front, lower side of the tally platen through an opening 82 in the deflector 60. The pressure roll comprises a core 83 and a sheath of rubber 84. The core is recessed at each end as indicated at 85 to provide seats for anti-friction balls 86 which coöperate with a rod 87 that passes loosely through the core 83, a ball bearing support for the pressure roll 81 being thus provided. Sleeves or washers 88 on the rod 87 retain the balls 86 in their seats, these sleeves in turn being maintained in place by nuts 89 which are screwed on the reduced and threaded portions of the rod 87. The extreme ends of the reduced portions outside 115 the nuts are smooth and engage in bearing openings in parallel arms 90, said arms being comprised in a rocking frame which further includes a cross rod 91 connecting the rear ends of said arms, the ends of said 120 cross rod being reduced to provide supports for said arms 90. The rocking frame is pivotally supported on a rod 92 which is secured at its ends in two of the hangers or brackets 78 and is arranged above the frame rod 11. The parallel arms 90 are perforated to provide bearing openings that co-operate with said rod 92. Spacing washers 93 on the rod 92 separate the arms 90 from the hangers 78 and maintain the rocking 125 130

frame in proper position lengthwise of the platen 17 with which the feed roll 81 co-operates. A coiled spring 94 hooked over the rod 91 and anchored to the frame rod 77 tends constantly to turn the rocking frame on its pivot and maintain the pressure roll 81 in co-operation with the tally platen 17. The rocking frame is controlled by a hand operated release frame comprising a U-shaped bail 95 which is pivoted loosely on the rod 77. The parallel end portions of said bail are curved to provide cam faces 96 terminating in dwells or seats 97, these end portions fitting into the spaces between the body of the rod 91 and the parallel arms 90 so that the cams 96 may co-operate with the reduced end portions of said rod 91. A finger piece 98 secured to the body of the bail 95 adapts it for convenient manipulation. When the bail is in the Fig. 6 position the spring 94 is effective to maintain the pressure roll 81 in engagement with the tally platen. By pressing the finger piece 98 forward the releasing bail 95 is rotated to the Fig. 7 position and during this movement the cams 96 operate on the rod 91 to rock the rocking frame on its pivot and release the pressure roll 81 as shown in said Fig. 7, said pressure roll being retained in this position by the co-operation of the seats 97 with the ends of the rod 91. The tally pressure roll 81, it will be understood, is thrown on and off at will and entirely independently of the pressure or feeding devices that co-operate with the main platen and with the device 54 which is in effect a supplementary rotary paper support. It is further to be understood that when the device 54 is employed to assist in feeding a wide sheet extending rightward from the main platen 16, the tally pressure roll 81 is released and locked off as in Fig. 7. This tally pressure device is used for a different character of work, for example, where two tally strips and a carbon inlay are employed in connection with a non-superposed work sheet, one tally strip being fed from the delivery tally roll to the receiving tally roll and wound on the latter while the other strip is not wound on the receiving roll but is left free to be torn off at intervals. The pressure roll 81 is particularly useful in feeding the outer or free tally strip which otherwise would not be advanced since it is not drawn off the delivery tally holder or spool by the rotation of the receiving tally holder.

The tally strip mechanism proper is mounted, as shown in Figs. 1 and 2, on a supporting frame comprising, as in my prior construction aforesaid, upright end plates or arms 99 and 100 and a connecting cross bar 101 bifurcated at its ends and receiving screws 102 by which the arms and cross bar are secured together, forming a single rigid support or frame. Said support is mounted on the cross rod 12 of the platen frame, the same passing through the arms 99 and 100. The latter has a hub 103 into which is threaded a set screw 104 that engages the rod 12. The supporting frame is arranged near the right-hand end of the rod 12 so that the tally holders mounted on said frame are directly above the tally platen 17. The delivery roll holder or tally supply spool 75 105 is mounted at the top of the supporting frame on a shaft 106 and comprises, as best shown in Fig. 13, a tube 107 having hub portions 108 and 108^a, the tube being slotted at 107^a to afford a passage for a bowed spring 109. Said spring is suitably secured to the tube and is adapted to co-operate with the core of the tally supply roll in order to frictionally connect said supply roll with the tube or core 107 of the roll holder. The hub portion 108 of said holder receives a set screw 110 by which the tube is fixedly secured to the shaft 106. A flange or head 111 is arranged at the left of the tube and its hub receives a set screw 112 by which the flange is adjustably secured. A socket piece 113 is fixed to the shaft 106 at the right-hand end of the tube 107 as by a set screw 114, said socket piece being depressed at 115 to receive a friction disk 116. The depression fits over and co-operates with the head 117 of a screw 118 which screws into the upper end of the arm 100 and is fixed in place by a locking nut 119. At its left-hand end the shaft 106 is coned or pointed as indicated at 120 and engages in a corresponding depression in a bearing pin 121 slidable in the arm 99 and provided with a flange 122 and a knurled finger portion 123 between which said pin is engaged by the bifurcated 105 upper end of a leaf spring 124 which is secured by a screw 125 to the arm 99. The spring tends constantly to press the pin inward and maintain it engaged with the shaft 106 but the construction permits ready withdrawal of the pin from the shaft so that the latter, together with the tally supply roll, may be removed and replaced. The supply holder and its mounting differ somewhat in detail from the prior construction. The 110 tally receiving roll holder, spool or carrier 126 is mounted below the delivery holder or the supporting frame and is preferably of the construction disclosed in detail in my prior application aforesaid, being mounted 115 on and frictionally connected to a shaft 127 which bears in the arms or bars 99 and 100. The frictional connections between the holder 126 and the shaft 127 comprise a knurled flange 128 integral with the holder 125 and formed with a depression which co-operates with a circular friction plate or device 129 secured to the shaft near its left-hand end, by a screw 130, a friction spring (not shown) being interposed between the 130

plate 129 and the bottom of the depression in the flange 128.

As shown in Figs. 1 and 2 there is arranged on the shaft 127 to the right of the holder 126 and between it and the arm 100, a pinion 131 having a hub 132 which receives a set screw 133 by which said pinion is secured to the shaft. Suitably fixed to the end portion of said shaft outside the arm 100 are two pinions 134 and 135, the pinion 134 corresponding in diameter and number of teeth with the pinion 131, while the pinion 135 is of less diameter and has fewer teeth. The pinion 135 is intended for cooperation with line indicating or counting devices hereinafter described and is adapted to connect such devices with the tally receiving spool 126. The pinions 131 and 134 are respectively connected through pinions or idlers 136 and 137 with the gear wheels 53 and 55. The idlers 136 and 137 are in the present instance mounted loosely on the frame rod 12 respectively at the left and at the right of the arm 100. A notched collar 138 suitably secured to the outer end of said shaft prevents displacement of the idler 137, while a collar 136^a fixed to the frame rod 12 may prevent leftward displacement of the idler 136. Secured in fixed relationship with the idler 136 is a saw tooth detent wheel 139 at the rear of which is arranged a cooperating roller detent 140 mounted on a spring arm 141 which is secured by a screw 142 to the rear of the cross rod 101. The idlers 136 and 137 and the detent wheel 139 may, however, be otherwise mounted, and in my application, Serial No. 765,145, I have shown tally roll gear connections of a similar character mounted on the hand controlled hollow shaft which bears on the frame rod 12. This gives a very compact construction of mechanism and enables a variety of tally strip constructions adapted for use in connection with various commercial systems and forms of work to be embodied in a single typewriting machine. In the present instance, it will be observed, there are provided two parallel trains of gear devices one arranged at each side of the knurled device 54, these trains connecting the ratchet wheel 56 with the tally platen 17, and the two sets or trains being necessary in order to bridge or get around the device 54 which is independent of both the tally platen and its line spacing wheel 56 but is interposed between these two parts.

The two platens or platen sections, as has been stated, are adapted to be actuated by the same line spacing devices and these devices act on the actuated devices or line spacing ratchet wheels 29 and 56 of the respective platens. These line spacing devices will now be described after a brief reference to the detent devices which control the platens between line spacing actuations.

It will be understood that the roller detent 140, acting on the detent wheel 139, will maintain all connected parts in adjusted positions and these connected parts include the tally platen 17 and its line spacing wheel 56. Detent devices are also provided for cooperation with the ratchet wheel 29 of the main platen 16, said last named detent devices comprising as shown in Fig. 1, a roller detent 143 that cooperates with said line spacing wheel at the top thereof, said detent being mounted on a spring arm 144 which is secured by a screw 145 to the platen frame. The hand controlled line spacing devices which cooperate with the ratchet wheels 5 and 29 to turn them and through them the main and tally platens comprise, as illustrated in Figs. 1, 2, 10, 10^a and 11, a pawl 146 having a hub 147 and which is slidably and rotatably mounted on a stud 148 extending laterally from an arm or carrier 149 into which it is threaded, said stud being fixed to said arm by a nut 150. The arm 149 bears loosely on the sleeve 44, being confined between the flange 48 and the right-hand end plate 10. Also bearing on said sleeve to the right of the arm 149 is an adjustable arm 151, said arm being off-set rightward at its top and providing a support for a spring plunger 152, the latter having a tooth 153 which is adapted to engage with a series of notches 154 on a member 155 which is adjustably secured by a screw 156 to the outer face of the right-hand end plate 10. The member 155 carries a pin 157 which extends laterally into the path of the arm 149 and provides a support against which said arm rests normally. It will be understood that this support may be adjusted by varying the engagement of the plunger tooth 153 with the notches 154. In this way the normal location of the pawl 146 which depends from the stud 148 may be varied. The parts as thus far described correspond with those found in the Remington No. 11 machine except that in the machine the pawl 146, while adapted to swing freely on the stud 148, is not adapted for sliding adjustment or setting on and longitudinally of said stud. The devices for actuating the pawl 146 at line spacing operation comprise an arm 158 pivoted loosely on the stud 148 to the right of the pawl 146 and having a lateral pin 159 which engages in an enlarged hole 160 in the arm 149, thus giving the arm 158 a lost motion connection with the arm 149. Below its pivot the arm 158 is pivotally connected at 161 to a link or rod 162, said link connecting the arm 158 with manual line spacing devices of the usual construction comprising a bell crank 163 pivoted at 164 to the right-hand end bar 8, the other arm of said bell crank being connected by a link 165 with a crank arm 166 secured by a screw 167 to a rock shaft 168.

6 bearing in a housing 169 on the right-hand end bar 8, said housing containing a restoring spring 170 for the line spacing devices, said spring being coiled around the rock shaft 168. Forward of the housing the rock shaft is shaped to provide a downwardly extending handle or line spacing lever 171 which when pulled or pressed rightward operates through the described train of connections to actuate the pawl 146. The lever 171 also restores the carriage from left to right. Said pawl is adapted to be shifted or set at different positions along the stud 148 so that the tooth 146^a in which said pawl terminates at its lower end may be adapted for engagement alternatively with the ratchet wheels 56 or 29 or for simultaneous engagement with both of said ratchet wheels. The shifting devices are adapted both for an automatic shifting during traveling movements of the carriage and for being manually shifted at will. The shifting devices are illustrated in Figs. 1, 2, 10, 10^a and 11. Said devices are supported on a bracket member or support 172 which is secured to the front of the right-hand end plate 10 of the platen frame by screws 173. Said devices comprise a shift plate or device 174 which may be made of sheet metal, said device having two parallel fingers 175 which curve rearward and upward and are separated so that there is provided between them a slot or passage-way 176. This slot receives a pin or device 177 which projects forward and upward from the pawl 146 and is secured thereto. The plate 174 has downwardly extending ears 178 which receive screws 179, said screws securing the plate 174 to a slideable toothed member or rack bar 180. This rack member is rectangular in cross section and is formed at its forward side with a series of teeth 181.

The rack member is slidably supported in a cut-out or track-way 182 cut or formed in the front upper face of the bracket 172, thus adapting the plate 174 for sliding movement on said bracket. Slidable movements are communicated to the rack bar 180 and through it to the plate, controlling member or pawl shifter 174 by devices comprising a mutilated pinion 183 mounted at the top of a vertical shaft 184 which shaft bears at its ends on pivot screws 185. The lower pivot screw is secured in an ear or lug 172^a projecting leftward from the lower end of the bracket 172 while the upper pin is secured in a short lug 172^b projecting forward from the top of the bracket between the ears 178, these ears being adapted to operate at their inner faces with the sides of the lug 172^b to limit sliding movements of the controlling member or shifter 174. The teeth with which the pinion 183 is provided mesh constantly with the teeth 181 so that 65 rotary movement communicated to said

pinion will be transmitted to said rack, causing the rack and the shifter 174 to slide or move correspondingly. This sliding movement will be transmitted by one or another of the fingers 175 to the pin 177 and through it to the pawl 146, actuating said pawl which will slide on the stud 148, the pawl as a result being brought into working position opposite either the ratchet wheel 29 as in Fig. 10^a or the ratchet wheel 56 as in Figs. 1 and 2 or into an intermediate position as in Fig. 10 in which the pawl is adapted to coöperate simultaneously with both of said ratchet wheels. In order to maintain the pawl set in either of these three positions retaining or detent devices are provided, the same comprising a series of, in the present instance three, shallow, circular depressions 186 formed in the under face of the rack bar 180. Adapted to coöperate with these depressions in a ball detent 187 seated in a depression in the bottom wall of the cut-out 182 and constantly urged upward by a coiled compression spring 188 which is housed in a depression below the ball seat. 90 The pawl shifter 174 and the pawl 146 will be retained set in one or another of the working or normal positions according as the ball detent 187 is engaged with one or another of the depressions 186, each of these depressions corresponding with one of the set positions. It will be understood that while the controller 174 retains the pawl 146 in set position transversely of the ratchet wheels 29 and 56, said controller does not interfere with the line spacing actuations of said pawl during which the pin 177 will move freely back and forth longitudinally along the slot 176.

The pawl controller 174 and pawl 146 are 105 adjusted by means operative to turn the shaft 184 and pinion 183. Said means, as illustrated in Figs. 1, 2, 10^a and 11, comprise a sleeve 189 which surrounds and is slidably supported on the shaft 184. The sleeve is 110 provided at its top with an upwardly extending finger 190 which engages slidably in a slot 191 cut in the front of the mutilated pinion 183, the construction permitting up and down sliding movements of the sleeve 115 relatively to its supporting shaft but preventing relative rotary movement between the parts. At its lower end the sleeve 189 is provided with two radially extending fingers 192 and 193. A finger piece 194 is 120 screwed into a threaded opening in the sleeve and is adapted for sliding the sleeve up and down on the shaft 184 and also for manually turning the sleeve and through it the shaft 184 and the connected rack and pinion devices. Detent devices are provided for retaining the sleeve in longitudinally adjusted positions with respect to the shaft 184. Said devices comprise depressions 195 and 196 spaced apart along the shaft 184 and a co- 125 130

operating ball detent 197 which is pressed constantly toward the shaft by a spring 198 seated in a depression 199 in the finger piece or handle 194. These detent devices 5 serve to retain the sleeve in two positions lengthwise of the shaft, one of these positions being illustrated in Fig. 1 where the detent 197 is seated in the depression 195; the other position being illustrated in Fig. 10 11 where the ball is seated in the depression 196. When the sleeve is set as in Figs. 1 and 2 the parts are adapted for automatic shifting of the pawl 146 and to accomplish this result an upright pin 200 on the top 15 plate 2 is provided for coöperation with the fingers 192 and 193, said fingers during to and fro movements of the carriage at this time following a path which is intercepted or obstructed by the pin or actuating device 200. The pin 200 is so located that with the 20 pawl controller 174 set to locate the pawl 146 opposite the ratchet wheel 29 of the main platen, said pin 200 will engage with the finger 193 during leftward traveling 25 movements of the carriage, and acting on said finger, will turn the sleeve 189 and shaft 184 and slide the controller 174 and pawl 146 leftward until the pawl is re-located in working position opposite the 30 ratchet wheel 56 of the tally platen. This re-location will take place as the main platen leaves the printing field and the tally platen enters the printing field, the result being that the line spacing devices will automatically 35 shift from the working relationship with the main platen as said main platen passes out of the printing field and will be automatically reset in working relationship with the tally platen as said tally platen 40 enters the printing field.

The shiftable line spacing devices will remain set as last described so long as the tally platen remains in the printing field or, in other words, so long as any part of the 45 paper or work sheet that is fed over said tally platen is opposite the printing point. If the carriage be returned toward the right far enough to carry the tally platen out of the printing field, and to 50 bring the main platen again within the printing field, the finger 192 will be brought into engagement with the actuating pin 200, causing the sleeve 189 to be turned to effect an opposite sliding movement of the controller 174 and pawl 146, this movement continuing until the pawl is 55 re-located opposite the ratchet wheel 29 where it will again operate under actuation of the lever 171 to turn the main platen. It 60 will be seen then that means are provided for automatically shifting and resetting the line space devices at predetermined points in the travel of the carriage and that as a result a single train of actuating devices 65 may be employed for coöperation, in alter-

nation in the present case, with a plurality of line spacing ratchet wheels or actuated devites and connected platens or platen sections. Further it will be understood that when the pawl operates to actuate the line spacing ratchet wheel 29 the main platen and the supplemental feeding device 54 will be turned independently of the tally platen 70 75 17 while when the ratchet wheel 56 is actuated the tally platen 17 will be turned and the main platen and connected parts will remain quiescent. The turning movements are communicated to the tally platen from the ratchet wheel 56 by the double train of gear connections heretofore described. Thus 80 85 90 95 100 105 110 115 120 125 130 135 rotary movement of the ratchet wheel 56 is transmitted through the pin 57 to the gear wheel 55, thence to the idler 137, from it to the pinion 134 which is rigid with the pinion 131 and with the tally receiving spool 126. Consequently the tally receiving spool will be turned automatically to wind the tally thereon when the parts are actuated as described. From the pinion 134 the motion is transmitted through the idler 136 to the gear wheel 53 rigid with the tally platen. As has been stated, in some systems of commercial work a main sheet may be employed which will extend rightward over the feeding device 54. Such sheet will be superposed on the tally strip, and in this style of work only a single tally strip is ordinarily employed together with a carbon inlay between the tally strip and the main work sheet. At this time the pressure roll 81 is locked out of use. In some systems of work however, for example, in listing, it is desirable to write two copies of the tally, and then usually a shorter work sheet coöperative only with the main platen is employed 105 together with two tally strips wound together with an interleaved carbon strip on the supply roller or spool 105. Of course, whether one or more tally strips are employed it or they are led off at the front of 110 said roll holder, as indicated in Fig. 2 where the tally sheet is designated as *p*, and thence down at the rear of the tally platen, around the same and up at the front thereof. In case one strip is employed, it is secured at 115 its free end to the receiving holder 126 so that it may be advanced and wound thereon when said receiving roll is turned. In case two tally strips are employed, the inner strip together with the interleaved carbon 120 sheet is wound as described, while the outer strip is torn off at intervals against the serrated device 61. A shearing or cutting device for the tally strip that is wound on the holder 126 is preferably provided, said device, as illustrated in Fig. 2, comprising a slotted bar 201 and a hand controlled cutting blade 202, the tally strip passing upward between said bar and said blade, so that it may be severed at desired intervals 130

by an actuation of said blade. These parts, however, are not *per se* of my invention and are not claimed by me. Where two tally strips or work sheets are provided and used as described the pressure roll 81 is thrown into use against the tally platen.

In some systems of commercial typewriting or in doing some special kinds of work it may not be desired to shift the actuator 10 or pawl 146 automatically as described and in such event the sleeve or slideable device, carrying the fingers or actuators 192 and 193, is shifted to the Fig. 11 position where said actuators are above and out of working 15 relationship with the pin 200. With the parts thus related the pawl 146 may be shifted at will by hand to coöperate with either of the line spacing ratchet wheels and will remain as long as desired in either position. Said pawl may also be shifted to and 20 set in an intermediate or central position as illustrated in Fig. 10 at which time the ball 25 detent 187 will be seated in the middle depression 186. Thus located the pawl tooth 146 will coöperate with both ratchet wheels 29 and 56 when actuated, resulting in a simultaneous turning movement of both platen sections which will operate as a single platen. This adapts the mechanism 30 among other uses for employment with a single continuous work sheet extending substantially throughout the combined lengths of platens and, of course, at such time a tally need not be employed.

In some kinds of work, for example, at 35 times when the machine is employed for listing purposes it is desirable to record the number of items comprised in the individual lists written on the tally strip or strips or on a work sheet that is fed over the tally platen, and accordingly line indicating or counting devices are provided such as illustrated in Figs. 1, 2, 12 and 14. As 40 in my prior application, Serial No. 746,303, the indicating devices proper comprise a co-operating dial and pointer construction set forth in detail in said prior application. Said dial and pointer is mounted on a swinging or pivoted arm 203 having a hub 45 portion 204 which bears rotatably on a cross rod 205 supported on the end bars 10 of the platen frame. The arm 203 provides a bearing for a shaft 206 having at one end a gear wheel 207 which is adapted to be 50 thrown into and out of mesh with the pinion 135 which, it will be remembered, is rigid with the tally receiving spool 126. The other arm of said shaft carries a beveled pinion 208 which constantly meshes with a 55 beveled gear wheel 209. Bearing rotatably on a pivot screw 210 and having fixed relationship with the beveled gear is a dial plate 211, and coiled around the hub of the 60 beveled gear between it and the dial plate 65 211 is a spring 212 which tends constantly

to turn the dial plate and normally maintains a stop 213 on said dial plate engaged with a stop 214 rigid on the arm 203, the inner end of said spring being secured to the dial mechanism and the other end to the 70 fixed stop 214. A pointer 215 secured to an arm 216 rigid on the arm 203 coöperates with the dial plate. When the arm 203 is swung forward on its pivot bringing the gear 207 into mesh with the pinion 135 line 75 space or advance movements communicated to the tally strip will be transmitted to the dial 211 which will turn correspondingly step-by-step. Consequently the pointer 215 will indicate on the dial the number of 80 items that have been written on the tally strip. When the arm 203 is swung back to the Fig. 1 position disconnecting the gear devices that connect the dial and pointer mechanism and the tally advancing mechanism, the spring 212 will restore the dial to normal position ready to begin a new series of counting operations when it is again connected with the tally strip winding devices.

In the present instance a spring is provided which constantly tends to throw the tally indicating mechanism back out of connection with the tally winding mechanism, and devices are also provided automatically operating during traveling movements of 90 the carriage to overcome the spring and to cause the connection of the counting mechanism with the tally winding mechanism at a predetermined point. Means are also provided for at will locking the dial in working 95 position. The restoring spring 217 for the dial and pointer mechanism is coiled around the rod 205 and at one end is secured to the hub 204, the other end being secured in a spring housing or socketed collar 218 100 secured by a set screw 219 to the rod 205. This spring tends constantly to throw the arm 203 rearward and maintain it disconnected from the tally mechanism. The rearward movement of the parts is limited by a 105 pin 220 on the hub 204 which is adapted to coöperate with the rear side of a cut-out 221 in the housing 218. A latch 222 pivotally supported on the housing 218 is adapted to be thrown down by hand behind the pin 110 when the parts are in working position, and when thus located will coöperate with the pin to hold the counting mechanism locked forward in connection with the tally mechanism. Ordinarily, however, the latch is inoperative as shown by dotted lines in Fig. 12, thus permitting the counting mechanism to be automatically controlled by devices which comprise an arm 223 fixed to the arm 203 and carrying at its lower end a roll 224 115 which is adapted to coöperate with a stationary cam plate 225, said cam plate having projecting ears 226 which receive screws 227, said screws securing the cam/plate in an upright position on the top plate behind 120

the rear guide rail 4 and near the right-hand side of the machine. The cam plate or bar 225 is provided at its right-hand end with a forwardly inclined portion or cam proper 225^a which is in the path followed by the roll 224 during traveling movements of the carriage. Consequently when in the course of leftward travel of the carriage the roller engages with the cam 225^a it will be forced rearward, swinging the counting mechanism forward into mesh with the tally feeding mechanism. This operation takes place as the tally strip enters the printing field and the roller 224 will remain engaged with the rear face of the cam bar 225 as long as the tally strip remains in the printing field. When the carriage is retracted and the roll 224 rides off the cam member the counting mechanism will be swung back by the action of the spring 217. Thus without care on the part of the operator, the counting devices are automatically brought into use when the associate work sheets or tally strip is in use or enters the printing field of the types and are automatically thrown out of use when said work sheet leaves the printing field.

Modifications may be resorted to without departing from my invention and an example of such modifications is illustrated in Fig. 15 wherein the feeding device or narrow annulus 54 is replaced by a platen section having a surface adapted to provide a suitable backing for type impressions. Said platen section, designated as a whole as 228, while comparatively short is of sufficient length to receive a considerable number of character impressions in a single line, and comprises a core of wood 229 and a sheath 230 of rubber 230. The platen 228 is driven on the right-hand end of the tube 24 and is rigidly related thereto and through said tube to the main platen 16, the two platen sections turning together independently of the platen section 17 which is intermediate or between them. The other parts are the same in construction and operation as has heretofore been described, except that obviously they may be re-located owing to the difference in length between the part 228 and the part 54 which it replaces. A pressure roll 231 may be provided for co-operation with the platen section 228. Said platen section has in addition to the feeding and supporting function of the device 54 the additional function of providing a surface against which printing may be effected on the sheet or portion of a sheet fed over said platen section 228.

Various changes besides those specified may be made without departing from my invention:

What I claim as new and desire to secure by Letters Patent, is:—

65 1. In a typewriting machine, the com-

bination of two connected platens, an independent platen intermediate said two platens, and a connection between said connected platens running through said independent platen.

2. In a typewriting machine, the combination of a platen, a support secured thereto, a second platen fixed to said support, and a third platen movable on said support.

3. In a typewriting machine, the combination of a platen, a support secured thereto, a second platen fixed to said support, and a third platen movable on said support, said third platen being intermediate said first and second platens.

4. In a typewriting machine, the combination of a rotary platen, a support mounted on and projecting from one end of said platen, and a plurality of additional platens on said support, one of said additional platens being fixed to said support and another of said additional platens being rotatable on said support.

5. In a typewriting machine, the combination of a rotary platen, a support carried by and projecting from one end of said platen, and a plurality of additional platens on said support, one of said additional platens being fixed to said support and another of said additional platens being rotatable on said support, said rotatable platen being arranged intermediate said fixed platen and said first recited platen.

6. In a typewriting machine, the combination of a rotary platen, a tube fixed to said platen and projecting from one end thereof, a paper supporting device secured to said tube, and an additional platen rotatable on said tube.

7. In a typewriting machine, the combination of a rotary platen, a tube fixed to said platen and projecting from one end thereof, a paper supporting device secured to said tube, and an additional platen rotatable on said tube, said additional platen being rotatable on said tube independently of said first named platen and of said paper supporting device.

8. In a typewriting machine, the combination of a rotary platen, paper feeding devices co-operative therewith, a paper supporting device carried by and rotatable with said platen, paper feeding devices co-operative with said supporting device, a second platen independent of and intermediate said supporting device and of said first named platen, and releasing devices for concurrently releasing the paper feeding devices of said platen and of said supporting device.

9. In a typewriting machine, the combination of a rotary platen, paper feeding devices co-operative therewith, a paper supporting device carried by and rotatable with said platen, paper feeding devices co-oper-

- ative with said supporting device, a second platen independent of and intermediate said supporting device and of said first named platen, releasing devices for concurrently releasing the paper feeding devices of said platen and of said supporting device, and other paper feeding devices adapted to be thrown into and out of coöperation with said second platen independently of said releasing devices. 10
10. In a typewriting machine, the combination of a rotary platen, a support connected thereto, a second platen rotatable on said support, a circular paper feeding device secured to said support, said second platen being arranged intermediate said device and said first named platen, two line spacing wheels arranged on said support at the opposite side of said device, connections 15 between one of said line spacing wheels and the intermediate platen, and connections between the other line spacing wheel and both the first named platen and also said device. 20
11. In a typewriting machine, the combination of a rotary platen, a support connected thereto, a second platen rotatable on said support, a circular paper feeding device secured to said support, said second platen being arranged intermediate said device and said first named platen, two line spacing wheels arranged on said support at the opposite side of said device, a rotary paper receiving holder, connections between one of said line spacing wheels and both 25 said paper receiving holder and also said intermediate platen, and other connections between the other ratchet wheel and both said first named platen and also said circular paper feeding device. 30
12. In a typewriting machine, the combination of means for supporting and feeding a plurality of work sheets, line spacing devices coöoperative with said means and operative by a single finger piece, and means 35 adjustable automatically to set said line spacing devices to afford an operation thereof to feed each of said plurality of work sheets independently of the other, said adjustable means being also adjustable by hand. 40
13. In a typewriting machine, the combination of means for supporting and feeding a plurality of work sheets, line spacing devices coöoperative with said means and operative by a single finger piece, and manual 45 means settable to afford an operation of said devices to feed each of said plurality of work sheets independently of the other or both of said work sheets together at will. 50
14. In a typewriting machine, the combination of means for supporting and feeding a plurality of work sheets, line spacing devices coöoperative with said means and operative by a single finger piece, and manual 55 means settable to afford an operation of said devices to feed each of said plurality of work sheets independently of the other or both of said work sheets together at will. 60
- devices to feed each of said plurality of work sheets independently of the other or both of said work sheets together at will, said manual means being also controllable automatically at will so as to afford an operation of the line spacing devices to feed either of said plurality of work sheets independently of the other. 70
15. In a typewriting machine, the combination of two platens, line spacing devices 75 operative by a single finger piece, and means adjustable manually to set said devices to line space said platens alternatively by an actuation of said finger piece or both of said platens simultaneously by an actuation of 80 said finger piece, said means being also settable at will to afford an automatic adjustment of said devices. 85
16. In a typewriting machine, the combination of two platens, line spacing devices 85 operative by a single finger piece, and means operative either automatically or by hand to afford adjustment of said devices to line space said platens alternatively as desired by an actuation of said finger piece. 90
17. In a typewriting machine, the combination of a traveling carriage, two platens thereon, platen line spacing devices operative by a single finger piece, and means operative during the carriage travel and comprising an adjustable device on the carriage to set and re-set said line spacing devices to line space first one platen and then the other by an actuation of said finger piece. 95
18. In a typewriting machine, the combination of line spacing mechanism comprising a plurality of wheels, and a single actuator shiftable to coöperate singly with any selected wheel, also shiftable to a position to coöperate simultaneously with a plurality of 100 said wheels. 105
19. In a typewriting machine, the combination of platen line spacing mechanism comprising a plurality of line spacing ratchet wheels, and a single hand controlled pawl shiftable transversely of said ratchet wheels to coöperate singly with any selected ratchet wheel, said pawl being also shiftable to an intermediate position to coöperate simultaneously with said plurality of 110 ratchet wheels. 115
20. In a typewriting machine, the combination of two platens, line spacing ratchet wheels one for each platen, a line spacing pawl, operative connections for said pawl 120 including a finger piece, means for shifting said pawl relatively to its connections to locate it in working relationship with either of said ratchet wheels so that either platen may be line spaced independently of the 125 other. 130
21. In a typewriting machine, the combination of two platens, line spacing ratchet wheels one for each platen, a line spacing pawl, operative connections including a fin-

- ger piece for said pawl, means for shifting said pawl relatively to its connections to locate it in working relationship with either of said ratchet wheels so that either platen 5 may be line spaced independently of the other, said means also affording a shifting movement of said pawl to position to co-operate simultaneously with both said ratchet wheels to line space the platens together.
- 10 22. In a typewriting machine, the combination of a divided platen comprising a plurality of co-axial sections, line spacing ratchet wheels arranged side by side one for each platen section, and a hand controlled line spacing pawl shiftable transversely of said wheels to adapt it for co-operation with either of them independently of the other.
- 15 23. In a typewriting machine, the combination of a divided platen comprising a plurality of co-axial sections, line spacing ratchet wheels arranged side by side one for each platen section, and a hand controlled line spacing pawl shiftable transversely of said wheels to adapt it for co-operation with either of them independently of the other, said pawl being shiftable also to an intermediate position to co-operate simultaneously with both ratchet wheels.
- 20 24. In a typewriting machine, the combination of a divided platen comprising a plurality of co-axial sections, line spacing ratchet wheels arranged side by side one for each platen section, a line spacing pawl, hand controlled actuating devices for said pawl, and means for shifting said pawl relatively to its actuating devices and transversely of said ratchet wheels.
- 25 25. In a typewriting machine, the combination of line spacing devices comprising a plurality of ratchet wheels, a co-operative line spacing pawl, hand controlled actuating devices for said pawl, and shifting devices for shifting and setting said pawl in positions to co-operate with either of said ratchet wheels, said shifting devices being controllable both automatically and by hand.
- 30 26. In a typewriting machine, the combination of line spacing devices comprising a plurality of line spacing ratchet wheels, a line spacing pawl, hand controlled actuating devices for said pawl, and means for shifting said pawl relatively to its actuating devices and transversely of said ratchet wheels, said shifting means providing also a guide for said pawl when it is actuated by said actuating devices.
- 35 27. In a typewriting machine, the combination of line spacing devices comprising a plurality of line spacing ratchet wheels, a line spacing pawl, hand controlled actuating devices for said pawl, and pawl shifting means comprising a slidable member having a pin and slot connection with said pawl, said connection permitting actuating move- ments of said pawl independently of said slidable member.
- 40 28. In a typewriting machine, the combination of line spacing devices comprising a plurality of line spacing ratchet wheels, a line spacing pawl, hand controlled actuating devices for said pawl, and pawl shifting means comprising a slotted slide member 70 co-operative with a pin or projection on said pawl, and detent devices co-operative with 75 said slotted slide member to maintain it in set positions.
- 45 29. In a typewriting machine, the combination of line spacing devices comprising a plurality of line spacing ratchet wheels, a line spacing pawl, hand controlled actuating devices for said pawl, a pawl shifter connected to said pawl, a shaft having rack and pinion connections with said shifter, and manual means for operating said shaft. 80
- 50 30. In a typewriting machine, the combination of line spacing devices comprising a plurality of line spacing ratchet wheels, a line spacing pawl, hand controlled actuating devices for said pawl, a pawl shifter connected to said pawl, a shaft having rack and pinion connections with said shifter, manual means for operating said shaft, and automatic means for also actuating said shaft. 90
- 55 31. In a typewriting machine, the combination of line spacing devices comprising a plurality of line spacing wheels, a line spacing pawl, hand controlled actuating devices for said pawl, a pawl shifter connected to said pawl, a shaft operatively connected to 95 said shifter, a slidable device on said shaft, and a stationary actuating device, said slidable device being settable in and out of position for co-operation with said stationary actuating device. 100
- 60 32. In a typewriting machine, the combination of a traveling carriage, line spacing devices comprising a plurality of line spacing wheels, a line spacing pawl or actuator, hand controlled actuating devices for said pawl, a shifter connected to said pawl, a stationary actuating device for said shifter, and means connected with said shifter and operative to maintain the same in and out of position for co-operation with said stationary actuating device during the carriage travel. 110
- 65 33. In a typewriting machine, the combination of line spacing devices comprising a plurality of line spacing wheels, a line spacing pawl, hand controlled actuating devices for said pawl, a pawl shifter connected to said pawl, a shaft operatively connected to said shifter, a slidable device on said shaft, and a stationary actuating device for 115 said shifter, said slidable device being settable in and out of position for co-operation with said stationary actuating device, said slidable device being provided with a finger piece for setting it, said finger piece also be- 120
- 70 66. In a typewriting machine, the combination of line spacing devices comprising a plurality of line spacing ratchet wheels, a line spacing pawl, hand controlled actuating devices for said pawl, and pawl shifting means comprising a slotted slide member 125 co-operative with a pin or projection on said pawl, and detent devices co-operative with said slotted slide member to maintain it in set positions. 130

ing adapted for actuating said shaft by hand to set said pawl through said pawl shifter.

34. In a typewriting machine, the combination of a traveling carriage, line spacing devices comprising a plurality of line spacing wheels, a line spacing pawl or actuator, hand controlled actuating devices for said pawl, a shifter connected to said pawl, a stationary actuating device for said shifter, means connected with said shifter and operative to maintain the same in and out of position for coöperation with said stationary actuating device during the carriage 10 travel, and detent devices for retaining said means in set positions.

35. In a typewriting machine, the combination of a traveling carriage, line spacing devices comprising a plurality of line spacing wheels, a line spacing pawl or actuator, hand controlled actuating devices for said pawl, a shifter connected to said pawl, detent devices for retaining said shifter in one or another of a plurality of set positions, a stationary actuating device for said shifter, means connected with said shifter and operative to maintain the same in and out of position for coöperation with said stationary actuating device, and detent devices for 25 retaining said means in a plurality of set positions.

36. In a typewriting machine, the combination of a traveling carriage, line spacing devices comprising a plurality of line spacing wheels, a coöperating line spacing pawl or actuator, hand controlled actuating devices for said pawl, a pawl shifter connected to said pawl, a shaft operatively connected to said shifter, a slidable device on said 40 shaft, a stationary actuating device coöperative with said slidable device during traveling movements of the carriage, and a support detachably mounted on said carriage, said pawl shifter, said shaft and said 45 slidable device being mounted on said support.

37. In a typewriting machine, the combination of a traveling carriage, line spacing devices comprising a plurality of line spacing wheels, a coöperating line spacing pawl or actuator, hand controlled actuating devices for said pawl, a pawl shifter connected to said pawl, a shaft operatively connected to said shifter, a slidable device on said 50 shaft, a stationary actuating device coöperative with said slidable device during traveling movements of the carriage, and sets of ball detent devices one set coöperating with said shifter and another set 55 with said slidable device.

38. In a typewriting machine, the combination of a traveling carriage, line spacing devices comprising a plurality of line spacing wheels, a coöperating line spacing pawl

or actuator, hand controlled actuating devices for said pawl, a pawl shifter connected to said pawl, a shaft operatively connected to said shifter, a slidable device on said shaft, a stationary actuating device coöperative with said slidable device during 65 traveling movements of the carriage, sets of ball detent devices one set coöperating with said shifter and another set with said slidable device, and a bracket member detachably mounted on said carriage, said pawl shifter, said shaft, said slidable device and said sets of ball detent devices all being supported on said bracket member.

39. In a typewriting machine, the combination of line spacing devices comprising a plurality of ratchet wheels, a coöperative line spacing pawl, an arm rotatable coaxially with said ratchet wheels, a stud or device mounted on said arm and slidably supporting said pawl, a link having a lost motion connection with said arm, a bell crank connected to said link, a rock shaft provided with a finger piece, a second link connecting said rock shaft with said bell crank, and pawl controlling devices for shifting said pawl transversely of said ratchet wheel on and relatively to said stud or device and for maintaining said pawl in predetermined positions to which it may thus be shifted.

40. In a typewriting machine, the combination of a plurality of rotary platens, devices for turning said platens comprising a single actuator, and automatic means for shifting said actuator for coöperation singly with said platens.

41. In a typewriting machine, the combination of a rotary platen; paper feeding devices coöperative therewith; a paper supporting device rotatable with said platen; paper feeding devices coöperative with said supporting device; a second platen independent of said supporting device and of said first named platen; releasing devices for concurrently releasing the paper feeding devices of said platen and of said supporting device; and other paper feeding devices comprising a rocking frame and a pressure roller on said frame adapted to be thrown into and out of coöperation with said second platen independently of said releasing devices.

42. In a typewriting machine, the combination of a rotary platen; paper feeding devices coöperative therewith; a paper supporting device rotatable with said platen; paper feeding devices coöperative with said supporting device; a second platen independent of said supporting device and of said first named platen; releasing devices for concurrently releasing the paper feeding devices of said platen and of said supporting device; other paper feeding devices com-

prising a rocking frame and a pressure roller on said frame adapted to be thrown into and out of coöperation with said second platen independently of said releasing devices; and releasing devices for said rocking frame comprising a bail provided with a finger piece and formed with releasing cams, said cams terminating in dwells or seats for retaining said rocking frame in released position.

43. In a typewriting machine, the combination of a platen, a rocking frame comprising side arms and a connecting cross bar, a feed roller mounted on said rocking frame and coöoperative with the platen, a spring for said rocking frame constantly pressing said feed roller toward the platen, and releasing devices coöoperative with said rocking frame and comprising a pivoted bail having releasing cams and provided with seats engaging said cross bar to retain said feed roller in released position.

44. In a typewriting machine, the combination of a platen, a feed roller, a rod extending through said feed roller, ball bearings between said rod and said feed roller at each end of the latter, retaining sleeves, parallel arms supporting said rod, a connecting cross rod, and releasing devices.

45. In a typewriting machine, the combination of a rotary platen, a paper supporting device rotatable with said platen, a second platen intermediate said first named platen and said paper supporting device, a pair of line spacing wheels at the opposite side of said paper supporting device, one wheel being connected to the first platen, and parallel trains of connecting devices at opposite sides of said supporting device, said trains connecting said second platen with the other line spacing wheel.

46. In a typewriting machine, the combination of a rotary platen, a paper supporting device rotatable with said platen, a second platen intermediate said first named platen and said paper supporting device, a pair of line spacing wheels at the opposite side of said paper supporting device, one wheel being connected to the first platen, and parallel trains of gears arranged in planes at opposite sides of said supporting device, said trains of gears connecting said second or intermediate platen with the other line spacing wheel.

47. In a typewriting machine, the combination of a rotary platen, a paper supporting device rotatable with said platen, a second platen intermediate said first named platen and said paper supporting device, a pair of line spacing wheels at the opposite side of said paper supporting device, one wheel being connected to the first platen, and parallel trains of gears arranged in planes at opposite sides of said supporting

device, said trains of gears connecting said second or intermediate platen with the other line spacing wheel, and a tally strip holder for receiving a tally strip that is fed over said second or intermediate platen, said tally strip holder being connected with said trains of gears.

48. In a typewriting machine, the combination of a rotary platen, a paper supporting device rotatable with said platen, a second platen intermediate said first named platen and said paper supporting device, a pair of line spacing wheels at the opposite side of said paper supporting device, one wheel being connected to the first platen, parallel trains of gears arranged in planes at opposite sides of said supporting device, said trains of gears connecting said second or intermediate platen with said second line spacing wheel, a detent wheel connected with certain of said gears, and a spring pressed detent coöoperative with said detent wheel to maintain said second platen and its connected line spacing wheel in set positions.

49. In a typewriting machine, the combination of tally strip mechanism, indicating devices, and means for automatically connecting said indicating devices and said tally strip mechanism.

50. In a typewriting machine, the combination of a traveling carriage, a work sheet thereon, line spacing devices for the work sheet, line indicating devices, and means for throwing said indicating devices into connection with said line spacing devices as said work sheet enters the printing field of the device during traveling movements of said carriage.

51. In a typewriting machine, the combination of a traveling carriage, a work sheet thereon, line spacing devices for the work sheet, line indicating devices, and means for throwing said indicating devices into and out of connection with said line spacing devices as said work sheet enters and leaves the printing field of the device during traveling movements of said carriage.

52. In a typewriting machine, the combination of tally strip feeding mechanism, indicating devices, and means for automatically connecting said indicating devices and said tally strip feeding mechanism, said means operating automatically as the tally strip enters the printing field.

52. In a typewriting machine, the combination of tally strip feeding mechanism, indicating devices, and means for automatically connecting and disconnecting said indicating devices and said tally strip feeding mechanism, said means operating automatically as the tally strip enters and leaves the printing field.

54. In a typewriting machine, the combination of tally strip mechanism, indicating

devices, and means for automatically connecting said indicating devices with said tally strip mechanism and for automatically disconnecting said devices and said mechanism.

55. In a typewriting machine, the combination of tally strip mechanism including tally line spacing devices, indicating devices operative by said line spacing devices, and means for automatically disconnecting said indicating devices and said line spacing devices.

56. In a typewriting machine, the combination of tally strip mechanism comprising a tally receiving holder, means for turning said holder, line indicating devices for the tally strip operative by said turning means, and means for automatically rendering said indicating devices inoperative by said turning means.

57. In a typewriting machine, the combination of tally strip mechanism, indicating devices, means constantly tending to maintain said indicating devices separated from said tally strip mechanism, and hand controlled devices for overcoming said means and maintaining said indicating devices connected to said tally strip mechanism.

58. In a typewriting machine, the combination of tally strip mechanism, indicating devices, means constantly tending to maintain said indicating devices separated from said tally strip mechanism, and hand controlled devices comprising a pivoted latch for maintaining said indicating devices connected to said tally strip mechanism.

59. In a typewriting machine, the combination of tally strip mechanism, indicating devices, means constantly tending to maintain said indicating devices separated from said tally strip mechanism, hand controlled devices comprising a pivoted latch for maintaining said indicating devices connected to said tally strip mechanism, and automatic connecting devices operative when said latch is ineffective.

60. In a typewriting machine, the combination of a traveling carriage, tally strip mechanism, indicating devices, and means operative automatically during traveling movements of the carriage to connect said indicating devices and said tally strip mechanism.

61. In a typewriting machine, the combination of a traveling carriage, tally strip mechanism, indicating devices, and means operating automatically at predetermined points in the travel of the carriage to connect said tally strip mechanism and said indicating devices and to disconnect said mechanism and said devices.

62. In a typewriting machine, the combination of a traveling carriage, tally strip mechanism, indicating devices, and means

operating automatically at predetermined points in the travel of the carriage to connect said tally strip mechanism and said indicating devices and to disconnect said mechanism and devices, said last recited means comprising a stationary cam member.

63. In a typewriting machine, the combination of tally strip mechanism comprising a tally receiving holder means for turning said holder, indicating devices comprising an indicating dial, a spring tending constantly to turn said dial in one direction, separable gears for connecting said dial with said holder, and automatic means for throwing said separable gears into and out of mesh.

64. In a typewriting machine, the combination of a traveling carriage, tally strip mechanism comprising a tally receiving holder, means for turning said holder, indicating devices comprising an indicating dial, a spring tending constantly to turn said dial in one direction, separable gears for connecting said dial with said holder, and automatic means operating at predetermined points in the travel of the carriage for throwing said gears into and out of mesh.

65. In a typewriting machine, the combination of a carriage, tally strip advancing mechanism, indicating devices, a pivotal support on which said devices are mounted, and means automatically operative to swing said support on its pivot to connect said indicating devices with said tally strip advancing mechanism.

66. In a typewriting machine, the combination of a carriage, tally strip advancing mechanism, indicating devices, a pivotal support therefor, devices adapted to connect said indicating devices with said tally strip advancing mechanism, spring means tending constantly to turn said support in one direction, and a stationary cam operative automatically during traveling movements of the carriage to overcome said spring and render said connecting devices effective.

67. In a typewriting machine, the combination of a traveling carriage, tally strip advancing mechanism, indicating mechanism connectible with said advancing mechanism, said indicating mechanism comprising a pivotal support, a pointer on said support, a co-operating dial on said support, dial stop devices, spring means for turning said dial on its pivot, said support being pivotally movable to connect and disconnect said dial with said advancing mechanism, and means operating automatically during traveling movements of the carriage for thus pivotally moving said support.

68. In a typewriting machine, the combination of a traveling carriage, tally strip advancing mechanism, indicating mechanism connectible with said advancing mechanism,

said indicating mechanism comprising a pivotal support, a pointer on said support, a co-operating dial on said support, dial stop devices, spring means for turning said dial on its pivot, said support being pivotally movable to connect and disconnect said dial with said advancing mechanism, an arm on said support provided with a roller, and a coöperating stationary cam, said cam and said roller operating automatically during travel-

ing movements of the carriage for thus pivotally moving said support.

Signed at the borough of Manhattan, city of New York, in the county of New York, and State of New York, this 17th day of 15 April, A. D. 1913.

CLIO B. YAW.
